(57) **CLAIM**

The ornamental design for a fastening device for a case for electronic equipment, as shown.

DESCRIPTION

FIG. 1 is a bottom plan view of a fastening device for a case for electronic equipment showing my new design;

FIG. 2 is a top plan view thereof;

FIG. 3 is a front elevation view thereof;

FIG. 4 is a right side elevation view thereof;

FIG. 5 is a left side elevation view thereof;

FIG. 6 is a rear, right side, top perspective view thereof; and,

FIG. 7 is a front, left side, bottom perspective view thereof. The tonal shading in the drawings is included for the purpose of illustrating the surface contours of the claimed design and forms no part thereof.
